DESIGN FOR A PHOTOGRAPHIC PRINTING MACHINE

Frederick G. Knowles, Rochester, N. Y., assignor
to Eastman Kodak Company, Rochester, N. Y.,
a corporation of New Jersey

Application July 23, 1947, Serial No. 140,472

Term of patent 14 years

(Cl. D61—1)

To all whom it may concern:

Be it known that I, Frederick G. Knowles, a citizen of the United States of America, residing at Rochester, in the county of Monroe and State of New York, have invented a new, original, and ornamental Design for Photographic Printing Machine, of which the following is a specification, reference being had to the accompanying drawings, forming a part thereof in which—

Fig. 1 is a perspective view of a photographic printing machine embodying my new design and taken from a position which shows the front, top, and one side wall.

Fig. 2 is a rear elevation of the photographic printing machine shown in Fig. 1.

I claim:

The ornamental design for a photographic printing machine, as shown.

FREDERICK G. KNOWLES.
